(57) CLAIM

The ornamental design for a seat belt compatible pet travel bed, as shown and described.

DESCRIPTION

FIG. 1 is a top, front perspective view of a seat belt compatible pet travel bed showing my design therefor;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Throughout the drawings the broken lines depict environment and form no part of the design.

1 Claim, 5 Drawing Sheets
